UNITED STATES PATENT OFFICE.

HARRY M. KORETZKY, OF BROOKLYN, NEW YORK, ASSIGNOR TO JOSEPH SATLOW, OF BROOKLYN, NEW YORK.

LAMP AND REFLECTOR HOLDER FOR FLASH-LIGHTS.

1,333,427.

Specification of Letters Patent.

Patented Mar. 9, 1920.

Application filed April 1, 1918. Serial No. 225,936.

To all whom it may concern:

Be it known that I, HARRY M. KORETZKY, a citizen of the United States, and a resident of the city of New York, borough of Brooklyn, in the county of Kings and State of New York, have invented a new and Improved Lamp and Reflector Holder for Flash-Lights, of which the following is a full, clear, and exact description.

10 This invention relates to flashlights, and has to deal more particularly with the holding means for the reflector and incandescent lamp.

15 The object of the invention is to provide a comparatively simple and inexpensive construction, reliable and efficient in use, and so designed as to insure good electrical connections between the terminals of the lamp, the battery and the switch, and also to prevent 20 the weight of the battery from acting on the lamp in a destructive manner.

25 A more specific object of the invention is the provision of a lamp reflector holder of that type which includes a metal disk having means for attaching the reflector thereto, and with which the movable contact of the switch is adapted to connect, there being novel means for attaching the reflector to the disk and insulated therefrom, and also novel 30 means carried by the disk but insulated therefrom for forming a protector for the lamp against the action of the weight of the battery, which protector also serves as an electrical connection with the central contact 35 of the lamp.

With such and other objects in view, the invention comprises various novel features of construction and arrangement of parts which will be set forth with particularity in 40 the following description and claims appended hereto.

In the accompanying drawing, which illustrates certain embodiments of the invention and wherein similar characters of reference 45 indicate corresponding parts in all the views,

Figure 1 is a side view of a flashlight with a portion in section to show the details of the invention;

50 Fig. 2 is an enlarged sectional view of the reflector and lamp holder and lamp protector;

Fig. 3 is a rear view of the lamp and reflector holder with portions broken away 55 and in section;

Fig. 4 is a detail sectional view of a modified form of the invention;

Fig. 5 is a detail sectional view of another modified form; and

Fig. 6 is a sectional view on the line 6—6, 60 Fig. 5.

Referring to the drawing, 1 designates the casing of an ordinary flashlight, which carries a switch 2 on the outside and contains a battery 3, a reflector 4, a lamp 5, and lamp reflector holding means A. The device A comprises a metal disk 6 which is secured to a disk of insulation 7 by spaced peripheral lugs 8 which are anchored in recesses 9 in the periphery of the insulation 7, and the center of this disk has an opening 10, the edges of which are helically formed to constitute a thread 11 with which the screw base 12 of the lamp 5 engages. The periphery of the metal disk 6 is adapted to be engaged by the 70 spring contact 13 of the switch 2.

The reflector 4 is connected with the insulation disk 7 by means of a metal disk 14 which has a central opening provided with a circular flange 15 which is beaded to the neck 16 of the reflector 4, and on the periphery of this disk 14, which is of less diameter than the metal disk 6, so that the contact 13 cannot engage with it, are peripheral lugs 17 interlocking with the recesses 18 in the periphery of the disk 7. The lamp and reflector holder forms a support for the protector for the lamp, which is interposed between the latter and the central terminal 19 of the battery 3. This protector is in the form of a metal bridge-piece 20 of U-shaped cross-section which is anchored at 21 in the disk of insulation 7, there being openings 22 in the metal disk 6 to prevent contact of the protector with the said disk. On this bridge-piece 20 is a spring metal contact 23 with which the terminal 24 of the lamp is adapted to engage, it being understood that the central terminal 19 of the cell bears against the bridge-piece 20, so that electrical connection is made through the latter and contact 23 with the central terminal of the lamp.

In Fig. 4 the construction is the same as that shown in Figs. 1 and 2, except that the metal disk 6 is made with a central threaded 105 socket 6^a to receive the screw base of the lamp.

In the construction shown in Figs. 5 and 6 the disk of insulation 7^a is bounded by a circumferential metal ring 25 which is electri- 110

2
cally connected by a pin 26 with the central screw on the socket 27 which is anchored in the central opening of the disk 7^a, so that when a lamp is inserted in the socket 27 the 5 metal base of the lamp will be electrically connected with the ring 25, which is adapted to be engaged by the spring contact of the flashlight switch. The protector 20^a has its extremities anchored in the disk 7^a. Attached to the disk 7^a is a plate 28 which has an annular flange 29 to which the neck 30 of the reflector 4 is beaded, said plate 28 being provided with anchoring lugs 31 which pass through the insulation 7^a.

10 Having thus described my invention, I claim as new and desire to secure by Letters Patent:

1. The combination of a reflector, an insulation piece having an aperture, a metallic 20 member anchored to the front side of the said piece and having an aperture provided with a forwardly extending flange, said reflector having an opening and provided with a flange having a beaded connection with the 25 first-mentioned flange, and a metallic member having a central portion forming a lamp-receiving means and a peripheral portion forming a contact.

2. The combination of a reflector, a member to which the reflector is rigidly fastened,

an insulation piece on which the member is anchored, a metal member attached to the insulation piece and having a central means for receiving a lamp socket, a peripheral portion adapted to form a contact, and a 35 lamp protector attached to the insulation piece to protect the base of the lamp when in position.

3. The combination of a reflector, a disk of insulation, means for attaching the reflector to the said disk, metal means having a central lamp-holding means and having its periphery extending beyond the periphery of the disk to form an annular electrical contact, and a lamp protector attached to the 40 disk and bridging the lamp-holding means.

4. The combination of a reflector, a disk of insulation, means for attaching the reflector to the said disk, a metal disk having a central lamp-holding means and having its 50 periphery extending beyond the periphery of the disk to form an annular electrical contact, a lamp protector attached to the disk and bridging the lamp-holding means, said protector being of metal, and a metal spring 55 contact carried by the protector for engagement by a lamp when inserted in the lamp-holding means.

HARRY M. KORETZKY.
